US00D554527S

(12) **United States Design Patent** (10) **Patent No.:** **US D554,527 S**
Oliver (45) **Date of Patent:** **** Nov. 6, 2007**

(54) **CONTAINER**

(75) Inventor: **Martin Oliver**, Runcorn (GB)

(73) Assignee: **Norton Healthcare Limited**, London (GB)

(**) Term: **14 Years**

(21) Appl. No.: **29/255,124**

(22) Filed: **Mar. 3, 2006**

(30) **Foreign Application Priority Data**

Sep. 6, 2005 (EM) 000397658-0001

(51) **LOC (8) Cl.** **09-01**

(52) **U.S. Cl.** **D9/696**

(58) **Field of Classification Search** D9/695-697, D9/707, 709, 417, 710-712, 500, 505, 545; 206/532, 528, 828, 484, 277; D24/121, 108, D24/224, 104; 222/92, 107, 541.5, 541.4; 215/382, 246

See application file for complete search history.
